UNITED STATES PATENT OFFICE.

THEODORE SCHIESS, OF NEW YORK, N. Y.

DESIGN FOR FABRIC-TRIMMING.

SPECIFICATION forming part of Design No. 33,012, dated July 24, 1900.

Application filed June 2, 1900. Serial No. 18,901. Term of patent 14 years.

To all whom it may concern:

Be it known that I, THEODORE SCHIESS, a citizen of the United States, and a resident of the city of New York, borough of Manhattan, in the county and State of New York, have invented and produced a new and original Design for a Fabric-Trimming, of which the following is a full, clear, and exact description.

Reference is to be had to the accompanying drawings, forming a part of this specification, in which—

Figure 1 is a plan view showing one side of a fabric-trimming of my design, and Fig. 2 shows the opposite side thereof.

The leading feature of my design for a fabric-trimming consists of a line of zigzag stitching along the edge of the fabric, the inner

meeting-points of said stitching at one side being shown in knotted or loop form, while the outer connecting ends of the loops forming the zigzag stitching are shown in double knots, and at the center of each of said double knots is a tufted or feather-like extension.

Having thus described my invention, I claim as new and desire to secure by Letters Patent—

The design for a fabric-trimming herein shown and described.

In testimony whereof I have signed my name to this specification in the presence of two subscribing witnesses.

THEODORE SCHIESS.
